TRAFFIC ACTUATED CYCLE LENGTHS SELECTOR APPARATUS

Garland E. Fieser, East Moline, and Frank W. Hill, Moline, Ill., assignors, by mesne assignments, to The Gamewell Company, Newton, Mass., a corporation of Delaware

Filed Apr. 10, 1958, Ser. No. 727,741
9 Claims. (Cl. 340—35)

The invention relates to means to select one of a plurality of cycle lengths at a local traffic signal controller. More specifically, the invention relates to means permitting the selection of traffic cycle lengths where a constant speed motor drives the cycle length controlling device through a series of successive speed reducers, each speed reducer permitting a choice of a plurality of ratios.

Preferably the relative choice of speed reductions at each speed reducer is different so that a device having N speed reducers, each with a plurality of ratios, gives a selection of different speeds equal to the plurality of ratios raised to the power equal to the number of speed reducers. For example, four speed reducers, each with a choice of two speeds, gives a choice of 2^4 or 16 speeds.

The several speed reducers are preferably built into one structure, having a plurality of axially movable shafts each located between an idler shaft. One axially movable shaft, together with two adjacent idler shafts, form one speed reducer.

Preferably the axially movable shafts are moved by a solenoid into one of the plurality of positions. In a simplified version, each movable shaft is biased to one of two positions and is shifted to its other position by an electric solenoid.

The invention provides means whereby a master controller at a central station can vary the traffic cycle created by a local traffic signal controlling device.

This may be accomplished by sending out signals from the master controller over a single channel to an electric channel selector at each intersection. The electric channel selector energizes the proper circuit to actuate the proper solenoid, each solenoid moving one of the movable shafts in a stepped speed transmission unit to one of its plurality of positions, thus enabling the constant speed motor at the intersection to drive the traffic signal controlling device at the proper speed. Such an electric channel selector is disclosed in patent application 473,080, filed December 6, 1954, now abandoned, and continued in application Serial No. 9,653, filed February 18, 1960, now U.S. Patent 3,605,188, by George Donald Hendricks, and in United States Patent 2,832,060, issued to George Donald Hendricks et al., April 22, 1958.

The principal object of the invention is to permit the choice of a large number of traffic cycle lengths by the proper selection of the speed reduction ratios in each of a number of successive speed reducers, each reducer capable of a plurality of speed reductions. The term traffic cycle length is defined as the time required for the traffic controlling signals to complete one full set of signal changes. In the usual street traffic controller it is the interval that elapses from the time green signal comes on to one lane, through amber and red until green signal comes on again.

Another object is to obtain precise, accurate control of traffic controller cycle speeds utilizing a synchronous motor and a remotely electrically shifted multi-speed transmission.

Another object is to remotely shift the proper gears of a multi-speed transmission with a number of solenoids controlled by an electric channel selector.

Another object of the invention is to shift the device to N different positions utilizing only $N/2$ solenoids and control conductors.

2

Another object is to secure at least two different traffic cycle lengths for each circuit actuating one of said speed reducers.

Reference will be made to the following figures, of which:

FIGURE 1 is a plan view of one form of the transmission and solenoid gear shifting apparatus.

FIGURE 2 is a section along 2—2 in FIGURE 1.

FIGURE 3 is a section along 3—3 in FIGURE 1.

FIGURE 4 is a partial view of a second form of the gear shifting apparatus utilizing push-pull solenoids on each shaft.

FIGURE 5 is a section parallel to elevation of apparatus shown in FIGURE 4.

FIGURE 6 is a schematic diagram of a gear shift mechanism incorporated into a local traffic controller and electrically connected to a master.

FIGURE 7 is a schematic diagram of the gear shift mechanism electrically connected to a signal impulse responsive electric channel selector in a local traffic controller.

FIGURE 8 is a schematic diagram of a plurality of traffic detectors, a master traffic controller of the computer type, an interconnecting cable connected at each local controller, a plurality of local controllers, each equipped with a gear shift mechanism and traffic light circuits.

Referring to FIGURE 1, the gear shift assembly 10 consists of a pair of side frame members 11 kept in parallel relationship by posts 12, and having a plurality of shafts 13 to 21 positioned therein. The input shaft 13 may be driven directly by the motor 22, or by a motor gear train combination 22, 23. Suitable bearings, not shown, are provided on the ends of each rotating shaft 13 to 21.

Positioned at alternate locations between the input shaft 13, the idler gear shafts 15, 17, 19 and the output shaft 21, are the axially movable gear shafts 14, 16, 18, 20. Each set of shiftable gears 25—26, 30—31, 34—35, 38—39 is positioned on an axially movable shaft 14, 16, 18, 20 which is free to rotate and free to slide in suitable bearings under urging from the operating solenoids 47, 48, 50, 51.

Each shiftable shaft 14, 16, 18, 20 is equipped with C-type return springs 43, 45, the shaft being free to turn in both ends of the spring. The ends of the shafts 14, 16, 18, 20 are equipped with rotatable collars 44 which have in them a groove for the end loop of the C springs 43, 45. Each shiftable shaft 14, 16, 18, 20 is also equipped with an operating mechanism consisting of an operating spring 45, an armature 46, and an electric solenoid 47, 48, 50, 51. Each solenoid and its flexibly attached gear shaft is operable singly or in combination with one, two, or all of the other solenoids to give the maximum number of gear ratios.

The choice of the proper gear ratio permits smooth progression from a given speed to a lower or higher speed in a number of approximately even steps. For purposes of illustration, the following ratios have been selected:

	Gear No.	Number of Teeth	Reduction
First reduction	25	23	23/25
	27	25	
Second reduction	31	22	22/26
	33	26	
Third reduction	34	20	20/28
	36	28	
Fourth reduction	39	16	16/32
	42	32	

To obtain a zero reduction, or a 1 to 1 ratio in the present embodiment, solenoids 47 and 50 must be energized. This was made necessary by space limitations and could be avoided by installing solenoids 47 and 50, with ac-

companying operating mechanisms, on the opposite frame member 11. Then, with all solenoids deenergized, a 1 to 1 ratio would result.

By energizing various ones of solenoids 47-50, singly or in groups, 16 different speed reductions are available.

Referring to FIGURE 1, with solenoids 47, 50 energized and solenoids 48, 51 deenergized, a 1 to 1 ratio between shafts 13 and 21 would result because the following gears would be in mesh with each other: 24, 26, 28, 30, 32, 35, 37, 38, 41. Since all of the gears have 24 teeth, a 1 to 1 ratio would result. We will call this condition 1.

Under condition 2, solenoid 50 would be energized and

33, 32 with 35, 35 with 37, 37 with 38, 38 with 41. All of the gears have 24 teeth except gears 31 and 33, which have 22 and 26 teeth respectively, resulting in a 22/26 reduction.

The detailed description of operation under conditions 1, 2, and 3 suffices to indicate the operation of the remaining conditions. The results of conditions 1 through 16 are outlined in Table I.

Table I shows that sixteen different speed reductions are available simply by energizing or deenergizing four solenoids. In the usual transmission one gear is shifted for each speed change desired; if 16 different speeds were desired, sixteen gears would have to be shifted.

TABLE I
Gear Reduction and How Obtained

Condition	Reduction	Solenoids				Gears In Operation (First Line) Teeth On Each Gear (Second Line)

14	$\frac{23}{25} \times \frac{29}{28} \times \frac{19}{32}=0.329$	Off	Off	Off	On	24-26-25-27-28-30-32-35-34-36-37-38-39-42 24-24-23-25-24-24-24-24-20-28-24-24-16-32
15	$\frac{23}{26} \times \frac{29}{28} \times \frac{19}{32}=0.302$	On	On	Off	On	24-26-28-30-31-33-32-35-34-36-37-38-39-42 24-24-24-24-22-26-24-24-20-28-24-24-16-32
16	$\frac{23}{25} \times \frac{23}{26} \times \frac{29}{28} \times \frac{19}{32}=0.278$	Off	On	Off	On	24-26-25-27-28-30-31-33-32-35-34-36-37-38-39-42 24-24-23-25-24-24-22-26-24-24-20-28-24-24-16-32

solenoids 47, 48, 51 deenergized, causing the following gears to be meshed: 24 with 26, 25 with 27, 28 with 30, 30 with 32, 32 with 35, 35 with 37, 37 with 38, 38 with 41. All of the gears operating under this condition have 24 teeth except gears 25 and 27, which have 23 and 25 teeth respectively, resulting in a 23/25 reduction between shafts 13 and 21.

Under condition 3, solenoids 47, 48, 50 are energized and solenoid 51 deenergized, causing the following gears to be meshed: 24 with 26, 26 with 28, 28 with 30, 31 with

Having described the solenoid actuated gear shifting apparatus, one application of this apparatus will be illustrated.

Referring now to FIGURE 6, the output shaft 21 of the gear shift mechanism 10 is suitably geared to the object to be driven, in this case a dial unit 61, of an intersection traffic controller. Such a dial unit is shown in United States Patent Number 2,815,410, issued December 3, 1957, to Frank Arthur Pearson et al. The dial unit 61 is one commonly used in intersection traffic controllers and is

shown here to illustrate the usefulness of the gear shift mechanism 10.

The dial unit 61 in its common form initiates impulses at preset intervals, to energize a solenoid 62 which steps a camshaft 63 of a step switch 60 to cause a change in signal lights in the traffic signal 64 energized through the light circuit contacts 65. A common form of the solenoid 62, camshaft 63, and light circuit contacts 65 is shown in United States Patent 2,815,410 mentioned above.

By transmitting electric current from a master traffic controller 66 located at a distant central station over one or more control conductors 52-59, the appropriate one of a number of cycle lengths can be selected.

The relationship between cycle length, motor speed, and gear ratio will now be explained. In this embodiment of the invention the speed of the motor 22 is a constant 60 r.p.m. The gear box 23 reduces this speed to 10.28 r.p.m. With the gear shift mechanism 10 shifted for a 1 to 1 ratio, the output shaft 21 will revolve at 10.28 r.p.m. A gear reduction of 6 to 1 is built into the dial unit 61. Thus, a speed of 1.71 r.p.m. or a cycle length of 35 seconds will result. The cycle lengths available in the present embodiment are as follows, but are not limited to the following:

TABLE II

Condition (See Table I)	Speed After Reduction, Percent	Cycle Length, Seconds
1.	100	35.0
2.	92.0	38.0
3.	84.6	41.4
4.	77.8	45.0
5.	71.4	49.0
6.	65.7	53.3
7.	60.4	57.9
8.	55.6	63.0
9.	50.0	70.0
10.	46.0	76.1
11.	42.3	82.7
12.	40.1	89.9
13.	35.7	98.0
14.	32.9	106.5
15.	30.2	115.8
16.	27.8	125.9

It is to be noted that the steps are in useful, even increments of approximately the same percent increase. This is necessary in traffic control if the device is to be utilized to the best advantage.

It is well known to those skilled in the art of traffic control that most expeditious traffic flow can be obtained by one certain cycle length for each set of traffic conditions along a highway. That is, one certain cycle length is best suited for a certain volume of traffic; the greater the traffic flow, the longer the cycle length. The proper cycle length can be determined from information gained from traffic studies. Also, the hourly and daily pattern of traffic flow can be determined by studying traffic counts, and traffic cycle changes programmed accordingly using a suitable program device. Such a program device is shown in patent application 481,891, filed January 14, 1955, by George Donald Hendricks, now Patent 2,832,071, issued April 22, 1958.

Electric impulse signals, originating in the programming device and transmitted to the various local controllers, thus put into operation the proper cycle length for each traffic condition.

In another application of the invention, the gear shift mechanism is equipped with a modified solenoid operating mechanism similar to the one shown in plan view in FIGURE 4, and in sectional view in FIGURE 5. Each shiftable shaft 14, 16, 18, 20 is equipped with two operating solenoids. Thus shaft 16 is equipped with solenoids 48, 68, one solenoid 48 to urge the shaft in one direction, and one solenoid 68 to urge the shaft back to its former position. A spring detent mechanism 69 retains the armature and gear shaft in its shifted position after the solenoids 48, 68 are deenergized. Thus, only a pulse of current is required to shift the mechanism. However, in

this form of the invention, double the number of control conductors 54, 55, 74, 75 are required, one pair for each solenoid as shown in FIGURE 5.

To overcome this disadvantage, the gear shift mechanism 81 is connected to an electric channel selector 82, FIGURE 7, of the type described in patent application 473,080, filed December 6, 1954, now abandoned and continued in application Serial No. 9,653, filed February 18, 1960, by George Donald Hendricks, and in United States Patents 2,826,752 and 2,832,060, issued to George Donald Hendricks et al., March 11, 1958 and April 22, 1958, respectively.

The electric channel selector 82, is also known as a local responder and is designed to permit the master traffic controller 83 at the central station to choose and energize any one of a number of functions at a plurality of local controllers 84. Thus, shifting of the gears at the local controllers 84 is accomplished by the master controller 83 on a programmed or traffic actuated basis.

In the programmed type a master controller chooses the cycle length at preset times. However, the traffic density may through any suitable device energize the electric channel selector 82.

The former arrangement is shown in schematic form in FIGURE 7. The master controller 83, under the control of a programming device 85, transmits impulses of 60 cycle alternating current at a frequency of approximately 10 impulses per second. The number of impulses sent is dependent upon the function desired, in this case 30 the gear ratio desired. The electric channel selectors 82 at the various local intersection controllers 84 maintain step with the master stepping device 86. The mechanism is disclosed in detail in application 9,653 and in Patents 2,826,752 and 2,832,060 mentioned above. When 35 the responder 82 has selected the terminal immediately ahead of the terminal connected to the selected gear shift solenoid 48 or 68 for example, a longer pulse is transmitted by the master stepping device 86 to step the electric channel selector 82 one additional step and to energize the solenoid 48 or 68 which shifts the proper gear in one of the pairs 25-26, 30-31, 34-35, 38-39, in this case, gears 30-31. Thus by successively moving one or more of the movable shafts 14, 16, 18, 20, cycle lengths can be programmed from the master controller 83 using 40 only a two conductor interconnecting cable 87 or other single channel.

In the operation of the invention the master controller 83 sends only a synchronizing pulse over lines 87 as long as the cycle length is to remain constant. The synchronizing pulse will not be registered by the electric channel selector 82.

When the cycle length is to be changed, the master controller 83 sends over lines 87 an appropriate number of short impulses followed by a long impulse. These impulses are received by a number of local controllers 84. 55 The electric channel selector 82 is each local controller 84 will respond to the number of short impulses and, upon receipt of the following the long impulse will place current on one of the solenoids 47, 48, 50, 51, 67, 68, 70, 71. This will change one gear ratio and thus change 60 the cycle length. The operating solenoids 47, 48, 50, 51, 67, 68, 70, 71 need not be continuously energized because spring detent mechanism 69 holds each shaft in its selected position.

65 In a typical application in traffic control it is usually desired that any change in cycle length, progression, offset, other function be made smoothly and not abruptly. The operation of the gear shift mechanism to effect change in cycle length is preferably made step-by-step, either 70 up or down, for smooth change from one cycle length to the next longer or shorter cycle length. For example, if the cycle length is 70 seconds (condition 9, Table I) and traffic conditions change so that the next longer cycle length is desired, it is only necessary that the master controller 83 transmit the appropriate coded pulses over

interconnecting cable 87 to each local electric channel selector 82, causing current to flow over line 73 to energize solenoid 67. Solenoid 67, becoming energized, shifts shaft 14 causing gears 25, 27 to mesh, resulting in further gear reduction in the ratio of 23 to 25. The total reduction of $10^{32} \times 2^{3/5}$ results in the desired cycle length of 76.1 seconds (condition 10, Table I).

The master controller 83 can send successive signals each consisting of a series of impulses, to actuate subsequent solenoids and put into effect various gear ratios. Because the axially-movable shafts 14, 16, 18, 20 are retained by spring detents 69 in the position to which they were last moved, an actuating impulse of only short duration is required. This frees the electric channel selector 82 for other duties. The actuating impulse must be of sufficient duration so that the solenoid 48, for example, exerts an attraction on the armature 46 which in turn exerts a force through C spring 45 on the movable shaft 16 causing gears 30, 32 to disengage and a moment later causing gears 31, 33 to engage.

To illustrate another application of the gear shift mechanism as used in traffic control, apparatus is shown in FIGURE 8 which is capable of detecting traffic in each lane of a highway, counting traffic in each lane per unit of time, discriminating which is the heavier rate of traffic flow, and adjusting the gear shift mechanism at each local controller to give a traffic cycle length for most expeditious traffic flow.

Referring to FIGURE 8, a plurality of local intersection traffic controllers 84 are shown each connected to an interconnecting cable 87 originating at a master traffic controller 83. Each local controller 84 and the master controller 83 is connected to an appropriate source of 115 volt alternating current power.

Located in, on, over, under, or near each traffic lane is a traffic actuated detector 90, which for purposes of illustration may be a pressure-sensitive type detector. Detectors of other types may be used, or combinations of types; however, to simplify the drawing and description pressure-sensitive type detectors are shown.

Uni-directional traffic detectors 90 are used in lanes on which traffic moves in one direction. Dual-directional or directionally selective traffic detectors, not shown, are used in the lane or lanes on which traffic moves in one direction at one time and in the opposite direction at other times. Such detectors are shown in United States patent application 723,038, filed March 31, 1958, by Garland E. Fieser.

Traffic detectors 90 are of the two contact type with one contact wired to ground through wire 91, and to low voltage relay coils 92, 93 through wires 94. The opposite ends of said relay coils 92, 93 are connected to a source of low voltage power 89, through wires 95. The primary coil 96 of the transformer is connected to a suitable source of 115 v. alternating current power through lines L1, L2.

Relay coil 92 is mounted on and a part of a suitable relay having contacts 97, 98, 99. Contacts 97, 98 are connected across capacitor C1. Capacitor C1 is connected between movable contact 98 and ground wire 104. Capacitor C2 is connected between a source of power L2 and a rectifier SR1, so that vehicular actuation of detector 90 in lane 105 closes a path to ground for relay coil 92 causing said relay to close contacts 98, 99 permitting capacitors C1, C2 to charge through rectifier SR1 from power source L1, L2. Opening of detector 90 circuit causes relay coil 92 to deenergize, opening contacts 98, 99, closing contacts 97, 98 shorting out capacitor C1. Capacitor C2 now discharges slowly through variable resistor R2. Further actuations of detector 90 in lane 105 repeat the cycle of charge causing capacitor C2 to carry a charge dependent on and representative of traffic density on the corresponding highway lane 105.

Relay coil 93 is similarly connected to a detector 90 in lane 106 and to a source of low voltage power 89 75

through wire 95. Actuation of the detector 90 in highway lane 106 similarly causes capacitors C3 and C4 to charge through rectifier SR3 and now-closed contacts 101, 103 from power source L1, L2. Opening of detector 90 circuit in lane 106 causes relay coil 93 to deenergize and open contacts 101, 103 and close contacts 101, 102, shorting out capacitor C3. Capacitor C4 discharges slowly through variable resistor R4. Continued actuation of detector 90 in lane 106 repeats the cycle of charge causing capacitor C4 to carry a charge representative of traffic density on highway lane 106. The ohmic value and setting of variable resistor R4 in relation to the value of capacitor C4 determines the drain-off time of capacitor C4 and consequently the duration of the averaging time interval. Increasing the ohmic value of variable resistor R4 increases the duration of the averaging interval.

Thus, circuit points 107, 108 are at potentials representative of the density of traffic upon highway lanes 105, 106, respectively. If traffic is heavier on lane 106 than 105, the voltage appearing at point 108 will be higher than that appearing at point 107.

Three components connected between points 107 and 108 form a discriminating circuit. Relay coil 110 is designed to pull in at a higher voltage than the voltage supplied by power source 111, and to drop out at a slightly lower voltage. Rectifier SR5 is provided to prevent a potential at point 107 higher than the sum of the battery 111 voltage plus the potential at point 108 from pulling in relay 110.

The voltage appearing across relay coil 110 is equal to the voltage supplied by power source 111 plus the potential supplied by capacitor C4, minus the potential supplied by capacitor C2. Thus, if the potential at point 107 is higher than that appearing at point 108, relay 110 will remain quiescent as shown in FIGURE 8 and will feed capacitor C2 potential to D.C. motor 112 over contacts 113, 114 through an amplifier A.

If the potential at point 108 is higher than that appearing at point 107, relay 110 will pull in and feed capacitor C4 potential to the D.C. motor 112 over contacts 114, 115, through an amplifier A. Thus, motor 112 is always fed with the higher of the potentials 107 or 108, representative of the higher rate of traffic flow.

Motor 112 is equipped to drive the wiper arms 121-124 of a rotary step switch device 120 and the rotary arm 116 of a potentiometer R6, which is a part of the rotary step switch 120. A D.C. potential is supplied to one end of the potentiometer R6 from capacitor C5 fed from a power source L2 through rectifier SR7. The other end of the potentiometer R6 is connected to ground. Thus, the voltage appearing across motor brushes 117, 118 is equal to the difference of potentials derived from the higher of capacitors C2 or C4 and the potential appearing at the tap on which rider 116 resides. If a change occurs in traffic flow rate, the potential at brush 117 will change and motor 112 will start to rotate, driving wiper 116 until substantially zero potential difference exists across the motor.

For example, if traffic flow rate on lane 106 increases, the potential at point 108 rises. If point 108 was already at a higher potential than point 107, relay contacts 114, 115 will have been closed. The increase in potential at point 108 is fed through amplifier A to motor brush 117, where it causes motor 112 to rotate wiper 116 to find a new position of substantially equal potential. Stepping switch wiper arm 116 carries the additional wipers 121-124 which control the operation of the gear shift mechanism 10 at each local controller 84.

The wiring of the step switch is also illustrated in FIGURE 8. Wiper arm 116 carries with it wiper arms 121-124 which switch L2 power to outgoing lines 52, 54, 56, 58 connected to solenoids 47, 48, 50, 51 as shown in FIGURE 6. The return lines for these solenoids are connected to one line 59 and return to the step switch 120 or are grounded at the controller 84.

On the step switch 120, L2 power is wired to each of those contact positions at which it is desired to energize the solenoid associated with that bank of the step switch.

For example in the topmost or 16th position of the step switch 120 as shown in FIGURE 8, wiper arm 121 is in contact with a segment not wired to L2, therefore not energizing conductor 52 and thus none of the solenoids 47 connected to it. Wiper arm 122 is in contact with a segment wired to L2, thus energizing conductor 54 and all solenoids 48 connected to it. Wiper arm 123 is in contact with a segment not wired to L2, not energizing conductor 56 and thus none of the solenoids 50 connected to it. Wiper arm 124 is in contact with a segment wired to L2, energizing conductor 58 and all solenoids 51 connected to it. As a result, condition 16, Table I, is placed in operation with gears shifted by the gear shift mechanism 10 to effect the longest cycle length, in this embodiment, 125.9 seconds.

As the density of traffic reduces, the potential of points 107, 108 reduces, causing a potential difference to appear 20 across motor brushes 117, 118. The potential difference results in motor 112 operating which moves wiper arm 116 to a tap of lower potential and wiper arms 121-124 to position 15, for example, which results in the energization of line 52 and all solenoids 47 connected to it. 25 The condition of lines 54, 56, 58 remains unchanged. The solenoids 47, 48, 50, 51 are in condition to give a cycle length corresponding to condition 15 or 115.8 seconds in this embodiment. Thus, change in traffic density results in change of traffic cycle length to allow most 30 expeditious traffic flow.

The invention is particularly suited to be used in connection with local traffic signal controllers of the type shown in United States patent application 642,469, filed February 26, 1957, and entitled Multiple Program Traffic Control System. The invention replaces a variable speed motor (60) which is normally used to drive a resynchronizing timer (62-67) and traffic cycle split controlling cams (100-106). Thus, one or the other of two optional traffic cycle duration determining means may be provided to satisfy the majority of timing requirements.

Having described several embodiments of the invention, we make the following claims.

We claim:

1. A traffic control system for accurately and exactly regulating the duration of a cycle of traffic signal change, including traffic signals at each of a plurality of intersections controlled by a plurality of respective synchronous traffic controllers, each of said controllers having a traffic signal energizing electric step switch, an electric impulse device connected to periodically step said step switch, a remotely shiftable speed reducer including a plurality of gear reductions, a constant speed synchronous motor driving said impulse device through said speed reducer, a master controller, a signal coding device at said master controller and a signal decoding device at each local controller interconnected by a single channel, means at the master controller to transmit a coded signal to each of said local controllers to shift at least one gear of said reductions to vary the length of a cycle of traffic signal change identically at each local intersection.

2. A traffic control system comprising:

a plurality of local traffic controllers; a master controller having program timer means for selecting different traffic cycle lengths at preset times; means for interconnecting said timer means of said master controller and said local traffic controllers; a gear changer including a constant speed driving motor in each of said local controllers; said gear changer controlled by said timer means through said interconnecting means; a step switch and traffic signal lights connected thereto in each of said local controllers; an impulse initiating means in each of said local controllers and driven by said gear changer for electri-

cally stepping said switch and thereby energizing and controlling said traffic signal lights through a plurality of selected traffic cycle lengths.

3. A traffic control system for regulating the duration 5 of a cycle of traffic signal change, including: a plurality of local synchronous traffic controllers; traffic signals at each of a plurality of intersections controlled by said local controllers;

each of said controllers having an electric step switch and an electrical impulse device connected to said switch for periodically stepping said step switch; each of said controllers having a remotely solenoidally shiftable speed reducer including a plurality of gear reductions, and a constant speed synchronous motor for driving said impulse device through said speed reducer;

a master controller;

a multi-conductor cable for interconnecting each of said local controllers and said master controller; and means at the master controller for energizing at least one of said conductors in said cable to shift at least one of said plurality of gear reductions at each local controller to accurately vary the length of a cycle of traffic signal change identically at each local intersection.

4. A traffic control system including in combination: traffic signals; local controls for controlling said traffic signals; local timer means and shiftable local gear reducer means in said local controls; said local gear reducer means for controlling the speed of said local timing means;

master controller means; master timer means electrically connected to said master controller means;

said master controller means acting in response to said master timer means and cooperating with said local gear reducer means for remotely shifting said gear reducer means to thereby remotely initiate a precise change in speed of said local timer means and exactly vary the length of a cycle of traffic signal changes.

5. In a traffic control system as in claim 4, said local gear reducer means having multiple gear reducer stages 45 shiftable singly and in combination to vary the speed of said local timer means in a number of increments, each of said increments when taken in ascending order being a substantially constant percentage of the prior lower speed.

6. In a traffic control system as in claim 4, said local gear reducer means having successive gear reducer stages, each stage having two orders of gear reduction and a 50 remotely controlled shifting means to thereby provide a number of possible speeds, said number of possible speeds being equal to two raised to a power which is the number of gear reducer stages.

7. A traffic control system comprising: a master traffic controller including program timer means to select at preset times one of a number of traffic cycle lengths; an interconnecting cable having a plurality of conductors on which current is placed by the master controller corresponding to the particular cycle length selected; and a plurality of local intersection traffic controllers to which said interconnecting cable is connected; each said local controller having a step switch, an impulse timer connected to impulse said step switch through a cycle of traffic signal change, a substantially constant speed motor, a remotely controllable multi-speed transmission coupling said motor to said impulse timer; each said multi-speed transmission connected to said interconnecting cable and being remotely controlled therethrough said program timer means to vary the length of said cycle.

8. A traffic signal control system including in combination: master traffic control means; traffic detectors in the traffic lanes of a roadway; individual electronic traffic

counting means for each direction of traffic flow on said roadway; each of said counting means adapted to produce an output proportional to the average rate of traffic flow counted thereby; amplifier means; electric balancing means connected to sense the output of each of said counting means, and adapted to connect the output of the counting means having the higher output to said amplifier means to provide an amplified D.C. output; stepping switch means including a stepwise potentiometer across a D.C. potential source, said stepping switch means including a plurality of contact banks each having a tap arm slideable thereover in unison with the movement of an arm of said potentiometer, said banks connected to a potential source to provide at each step switch position a distinct combination of tap arm conditions, a tap arm having two conditions as energized and non-energized from the last said source, step switch driving motor means connected between said potentiometer arm and the output of said amplifier means and adapted to drive said potentiometer arm in a forward or reverse direction until the potential across said driving means is substantially zero, said stepping switch means thereby caused to proportionally follow the traffic counting means whose output is higher; a plurality of local traffic signal controllers some of which are located at intersections along said roadway; and means interconnecting said stepping switch tap arms at the master control means to each of said local traffic signal controllers; each of said local traffic signal controllers comprising a remotely controlled multi-speed transmission, a constant speed motor driving said transmission, an impulsing means driven by said multi-speed transmission, a step switch impelled by said impulsing means, the traffic signals at each intersection connected to and controlled by said step switch of a respective local controller through successive cycles, electromechanical gear shift actuators operative in conjunction with said multi-speed transmission and controllable through said interconnecting means by said stepping switch means in said master control to vary the length of the traffic cycle in relation to traffic density in the direction of heavier flow.

35

40

486,171

9. Traffic signal cycle length control apparatus for traffic signals at each of a plurality of intersections along highway lanes: the apparatus at each intersection including a remotely controlled multi-speed transmission, a substantially constant speed motor driving said transmission, an electric impulse originating means driven at one of a plurality of constant speeds by said motor through said transmission, and a signal controlling device urged through one cycle of operation by electric impulses originating during one cycle of said impulse originating means; traffic control signal lights energized through said signal controlling device; traffic actuated detectors in each highway lane; a master controller including means connected to said detectors to detect and measure the time rate of traffic flow individually in each direction over the highway lanes, means responsive to measured said rates of traffic flow to determine the heavier rate of traffic flow, and means responsive to the rate of heavier flow to control the position of a reversible step switch device; and means connecting said step switch device in said master controller with each said remotely controlled multi-speed transmission to shift the transmission and effect precise change in the traffic cycle length proportional to the rate of traffic flow on the heavier lane.
